(57) **CLAIM**

The ornamental design for a night vision monocular, as shown and described.

DESCRIPTION

FIG. 1 is a front and right perspective view of a night vision monocular showing my new design;
FIG. 2 is a rear and left perspective view thereof;
FIG. 3 is a bottom perspective view thereof;
FIG. 4 is a front elevational view thereof;
FIG. 5 is a rear elevational view thereof;
FIG. 6 is a left side elevational view thereof;
FIG. 7 is a right side elevational view thereof;
FIG. 8 is a top plan view thereof; and,
FIG. 9 is a bottom plan view thereof.

The broken lines in the drawings depict portions of the night vision monocular that form no part of the claimed design.
